WATER CLOSET CONNECTION

John W. Szlapka, Chicago, Ill.

Application October 31, 1938, Serial No. 238,044

4 Claims. (Cl. 285—33)

This invention relates to a water closet connection, and more particularly to improved means for maintaining a tight connection between a water supply conduit and a toilet bowl.

One feature of this invention is that it provides and maintains a non-leaking seal between a toilet bowl and a water supply conduit; another feature of this invention is that it may be very readily and easily applied; a further feature of this invention is that it is adapted to be used with bowls of different types and sizes; yet another feature of this invention is that the connection between the bowl and water supply conduit is capable of withstanding great strain without leaking; other features and advantages of this invention will be apparent from the following specification and the drawings, in which

Figure 1 is a partial side elevation of a bowl and conduit embodying my invention; Figure 2 is a bottom plan view of the device shown in Figure 1; Figure 3 is a view, partly in section, along the line 3—3 of Figure 1; and Figure 4 is a view principally in section, along the line 4—4 of Figure 2.

The water conduit for a back supply bowl has heretofore been usually connected to the toilet bowl merely by a threaded telescoping member. While such a connection is satisfactory in the majority of cases, it has proved unable to withstand the strains imposed on it under certain circumstances. Toilet bowls having self-rising seats and seat-flushing valves, for example, cause considerable strain on the water supply connection, and it has been found that the conventional telescoping connection above-mentioned generally leaks when used with such bowls. Moreover, even where the valve is manually operative, it has been found that in some cases the toilet bowls receive such rough usage as to cause leakage at the inlet; this frequently occurs, for example, in schools or other public places where the bowls may be stood on or otherwise abused.

My invention provides and maintains a tight and non-leaking connection between the bowl and the water supply conduit by using a yoke and a pair of anchor bolts to firmly maintain the conduit in position with respect to the bowl.

In the particular embodiment of my invention illustrated herewith, a toilet bowl 10 of conventional type has in the back thereof an opening 11 for the supply of water. This opening is adapted to have connected thereto the water supply conduit, here shown as an elbow 12 adapted to supply water from a box, tank, or valve, or other source. The end of the conduit 12 adja-

cent the opening of the bowl is provided with an annular outwardly extending flange 13 of greater diameter than the opening.

Referring more particularly to Figure 4, it will be seen that an expansion washer or gasket 14 and an internally threaded telescoping member 15 of conventional type provide connection between the conduit 12 and the bowl 10. This connection is not here relied upon for maintaining these parts in tight relation, however, my invention providing further means whereby the flange 13 compresses the gasket 14 against the toilet bowl with great force.

This further means comprises a yoke plate 16 having an opening 17 therethrough adapted to encircle the conduit 12, the portion of the yoke plate 16 immediately about said opening being adapted to abut the flange 13 on the side thereof removed from the bowl. The yoke member or plate 16 is provided with reinforcing means 18 at this point, in the form of ridges thereon. In order to draw the yoke plate toward the bowl and thus maintain the flange, gasket and bowl in tight relation, tensioning means connecting the yoke to the bowl are provided.

The bowl, in conventional manner, is here shown as provided on opposite sides of the opening therethrough with seat posts 19 and 20, these posts having threaded shanks 21 and 22 extending through the shoulders or upper portion of the bowl as illustrated. The posts are adapted, in conventional manner, to support and provide the hinges for the seat 23 and cover 24.

The shanks of the seat posts are adapted to have mounted thereon to swivel therearound anchor bolts 25 and 26, the projecting portions of the bolts being preferably off center of the collar portions, as 27, encircling the shanks of the seat posts. Referring more particularly to Figure 1, it will be seen that the collar 27 of the anchor bolt 25 is held in place on the shank 21 of the seat post 19 by a nut 28 and an extension collar 29. This arrangement enables proper location of the anchor bolts with respect to the yoke on bowls of any thickness, since various combinations or arrangements of the parts 27 and 29 may be made.

Referring more particularly to Figure 3, it will be seen that the yoke member or plate 16 has at each end thereof, on opposite sides of the opening encircling the conduit 12, T-shaped open-ended slots 30 and 31. These slots are adapted to receive the anchor bolts 25 and 26, respectively, and the edges of the slots provide a bearing against which the nuts 32 and 33 on

such bolts may be drawn up. The fact that the slots are open-ended enables the bolts to be readily swiveled into place therein without removing the nuts completely therefrom; and the vertical portions of the slots enable further compensation for position of the anchor bolts 25 and 26 on various sizes and types of toilet bowls. When the nuts are drawn up on the anchor bolts considerable force is exerted on the yoke drawing it toward the toilet bowl. Because of its position behind the flange 13 of the water supply conduit 12 the yoke, as a result of such force, tightly compresses the expansion washer or gasket 14 to provide a tight connection. Moreover, because the placement of the bolts at some distance from the center of the conduit provides considerable leverage with respect thereto, a tight connection is maintained despite forces which would otherwise tend to displace or move the bowl with respect to the conduit.

In assembling the connection of the type here disclosed it is only necessary to slip the yoke plate over the conduit 12 before connecting it to the box or other source of water, and to slip the swivel anchor bolts in position on the shanks of the seat posts before tightening them in place on the bowl. The anchor bolts may then be swiveled into position in the yoke, and the nuts on the anchor posts tightened. It is then only necessary to draw up on the anchor bolts to provide the desired tight connection between the conduit 12 and the toilet bowl.

While I have described and claimed certain embodiments of my invention it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as permissible in view of the prior art.

I claim:

1. Apparatus of the character described for maintaining a tight connection between a flanged conduit and a hornless toilet bowl, including: a gasket adapted to lie between said bowl and the flange on said conduit; a yoke adapted to con-

tact said flange on the side removed from said bowl; and means engaging said bowl and said yoke and adapted to draw said yoke toward said bowl to maintain said flange in sealing engagement with said gasket.

5

2. Apparatus of the character described for maintaining a tight connection between a flanged water supply conduit and a toilet bowl having seat posts, including: a gasket adapted to lie between said bowl and the flange on said conduit; a yoke adapted to contact said flange on the side removed from said bowl; and tensioning means on opposite sides of said flange connecting said seat posts and said yoke and adapted to draw said yoke toward said bowl to maintain said flange in sealing engagement with said gasket.

10

3. Apparatus of the character described for maintaining a tight connection between a flanged water supply conduit and a toilet bowl having seat posts, including: a gasket adapted to lie between said bowl and the flange on said conduit; a yoke plate adapted to contact said flange on the side removed from said bowl, said yoke having open-ended T-shaped slots therein on opposite sides of said flange; and a pair of bolts 25 mounted on said seat posts to swivel therearound and adapted to be received by said slots, whereby drawing up on said bolts draws said yoke toward said bowl to maintain said flange in sealing engagement with said gasket.

20

4. Apparatus of the character described for maintaining a tight connection between a water supply conduit having an annular flange therearound and a toilet bowl having seat posts, including: a gasket adapted to lie between said bowl and the flange on said conduit; a yoke plate having an opening therethrough adapted to encircle said conduit and abut said flange on the side removed from said bowl, said yoke having open-ended T-shaped slots therein on opposite 40 sides of said flange; a pair of bolts mounted on said seat posts to swivel therearound and adapted to be received by said slots, whereby drawing up on said bolts draws said yoke toward said bowl to maintain said flange in sealing engagement 45 with said gasket; and means for readily adjusting the position of said bolts on said seat posts.

JOHN W. SZLAPKA.
